RALPH W. ARMSTRONG, OF NEW YORK, AND WILLIAM S. EVANS, OF ROSEBANK, NEW YORK, ASSIGNORS TO THE SAFETY CAR HEATING & LIGHTING COMPANY, A CORPORATION OF NEW JERSEY.

COMBINATION ELECTRIC FAN AND LAMP.

1,175,040.

Specification of Letters Patent. Patented Mar. 14, 1916.

Application filed May 23, 1913. Serial No. 769,365.

To all whom it may concern:

Be it known that we, RALPH W. ARMSTRONG, a citizen of the United States, residing in the borough of Manhattan, city, county, and State of New York, and WILLIAM S. EVANS, a subject of the King of Great Britain, residing in Rosebank, county of Richmond, State of New York, have invented a new and useful Improvement in Combination Electric Fans and Lamps, of which the following is a description.

This invention relates to apparatus for producing light and air on railroad vehicles, and has particular reference to a combination of means whereby an electric fan and an electric light are associated so as to practically conceal the fan and make the apparatus appear merely as an electric light fixture.

Among the objects of our invention may be noted the following: to provide a fixture so constructed as to support electric light parts and conceal therein an electric fan; to provide means for combining light and air producing apparatus for use particularly on railway vehicles; to provide a combination fixture having the light and fan parts so arranged as to avoid interference of the same with each other and have the appearance of a light fixture only; and to provide a simple, compact and effective structure by means of which a light fixture may be utilized also as a fan fixture, and by means of which the air can be deflected at the proper angle in the vehicle.

With the above objects in view, and others which will be detailed during the course of this description, our invention consists in the parts, features, elements, and combination of features and elements, as hereinafter described and claimed.

In order that our invention may be clearly understood, we have provided drawings wherein:

Figure 1 is an elevation of a structure embodying our invention and shown as attached to the ceiling and roof of a car, the parts of the latter being shown in section; and Fig. 2 is a sectional elevation taken vertically through Fig. 1 and showing the details of construction embodying our invention.

Referring to the drawings, the numeral 1

indicates the ceiling of a railroad vehicle such as a Pullman dining-car, 2 being the roof of said car. The ceiling may be constructed of "agosote," or any other suitable composition or material, and the roof is usually composed of steel. A superstructure is bolted to the roof 2 of the car and comprises the circular support 3, which is angular in cross-section. The horizontal portion of the support has a plurality of lugs or projections 4, which are slotted for the reception of bolts 5, pivoted at 5^a, and the free ends of which are screw-threaded and also headed at 6, the screw-threaded portions carrying winged nuts 7, which engage the notched flange 8, of a dome or cover 9, which encircles the support 3, and is securely fastened to the latter by the said bolts. To make the parts dust-tight, a rubber gasket 10 is arranged between the horizontal portion of the support 3, and the top surface of the roof 2, and another rubber gasket 11 is arranged between the upper edge of the vertical portion of the support 3, and the horizontal flange of the dome 9, the latter being grooved to receive said gasket 11, and the said upper edge of the support. Another annular angular support section comprising the depending member 12, horizontal member 13, and upwardly-extending member 14, has a plurality of preferably hollow bolts 15, extending upwardly 85 therefrom, which are rigidly secured to the member 13, and pass through the ceiling 1, roof 2, gasket 10 and horizontal portion of the support 3. The bolts are headed at 16, and have a screw-threaded portion to which 90 is applied a nut 17, for holding the upper support section 3, in fixed relation, and thus tightly clamping the member 13 of the second angular support section in position 95 against the inner surface of the car ceiling and the outer support section 3 against the roof of the car. Surrounding the member 14, is a sheet-metal casing sleeve 18, which extends from the member 13 to a distance within the member 3, as clearly shown in 100 Fig. 2; and in said figure it will also be seen that the gasket 10 extends into engagement with said sleeve 18. The upper edge of the member 14 affords a seat and support for the flange 19, of the casing of an electric 105 motor, which is thereby suspended within

the two upper support sections and shielded by the sleeve 18, and the head of which motor projects upwardly into the dome 9 of the superstructure. The motor-shaft 20 depends considerably below the lower edge of member 12, and has securely pinned to its lower end the hub 21 of a fan, the blades of which latter will be presently described. Rigidly secured, as by screws 22, to the depending member 12, is a metal filigree or open-work hoop or ring 23, the same being arranged to encircle the member 12 of said fixture and depend a short distance therebelow. An ornamental flange 24 may be applied to the ring 23, above the top thereof, as by screws 25, and arranged so as to encircle the support member 12 close to the ceiling 1 of the car. Secured to a flange 26, of the ring 23, is another annular support section 27, the horizontal flange 28 of which is grooved to receive the lower edge of the ring 23, thus making a neat and tight joint. The section 27 is provided with the curved, depending, inwardly-extending arms 29, which are preferably made U-shaped both for strength and to receive the electric circuit wires of a subjacent lamp. The curved arms 29 are connected at their lower ends with a circular flange or ornamental portion 30, to which is secured the horizontal flange 31, of the socket-support 32, of the lamp, said support being externally screw-threaded and having a central web 33, to which is secured the socket 34, for reception of the lamp-plug 35, supporting the usual electric light bulb 36.

The socket-support 32 has secured to its lower end the resilient shade-holder 37, the lower ends of the members of which are 40 conformed to the shape of the flange of the shade or globe 38, so as to securely hold the latter when compressed into engagement therewith by the clamp 39, having the interior screw-threaded flange 40, coöperating 45 with the external screw-threads of the socket-support 32. The leads 41 to the electric bulb extend in one or more of the arms 29, being housed and concealed by the latter, as clearly shown in Fig. 2. The bolts 15 50 may be utilized to convey the leads to the lamp and house the same, as shown by full and dotted lines at the point 42, at which point they leave the tube and are supported.

The hub 21 of the fan is provided with a 55 plurality of obliquely-arranged, curved, radial blades 43, the lower ends of which are secured together by means of a plate 44, secured to the flange 45, of the hub 21, and the upper ends of which are secured together 60 by a similar plate 46. Extending laterally from the plate 46 are a plurality of arms 47, each of which supports a fan-blade 48, extending radially from the fan-blades 43, and at an angle thereto. As shown in the 65 drawings, and particularly Fig. 1, the blades

43 are arranged circumferentially of the shaft 20, radiate from the latter and are curved longitudinally. These fans are also arranged vertically oblique with reference to the shaft 20. The fan-blades 48 are arranged substantially in a horizontal plane and slightly at an obtuse angle to the ends of blades 43, and also arranged vertically oblique, with reference to their transverse diameter, to the shaft 20. To this particular 75 arrangement of the two different sets of fan-blades we do not desire to be strictly limited, as our invention includes any fan blade arrangement which will result in drawing air into the chamber above the fan through the 80 air admitting filigree ring 23, or substantially in the direction of the arrows *a*, Fig. 2, and then deflect said air downward and outward through the support or casing openings between the casing arms 29, and substantially in the direction of the arrows *b*, Fig. 2. In other words, this important feature of our invention involves an idea of means by which air may be drawn into the chamber above the fan and then deflected by 90 the fan at an angle of substantially 45°, this angle being conceived by us to be an appropriate angle of distribution of the air above the heads of passengers, for example, in dining cars; and, as it is an object of our invention to properly draw in the air and distribute and deflect the same at an angle making the air currents agreeable to those seated below the fan, we desire it understood that an important feature of our invention is a means by which the air may be 95 properly distributed below the ceiling of a car or other vehicle and above the heads of those seated therein in such manner that they may not be exposed to direct injurious or disagreeable air drafts. The structure of fan described and shown has been found by us to satisfactorily carry out our ideas of invention and we have, in consequence, 100 illustrated the same as the best disposition 105 of parts as we now contemplate making our invention without, of course, being limited to the precise angles for the fan-blades shown in the drawings.

From the foregoing it will be seen that 115 we have provided an apparatus by means of which the ugly fan feature is eliminated, since the fan is practically invisible. At the same time, we have combined the merits of the fan with the light without destroying the merits of the lamp and while assuring the sightly and ornamental appearance of the whole apparatus.

It is believed to be new to make a combined fan and lamp comprising a support 125 or casing, an electric motor sustained at the upper part of said support or casing, an electric lamp sustained at the lower part thereof, and a fan arranged in an intermediate chamber of the support formed be- 130

- tween the motor and the lamp and operatively coupled to the motor, said support or casing having openings forming air passages to and from the fan chamber, preferably 5 separate air inlet and outlet openings respectively located above and below the upper plane of rotation of the fan. There also are novel features in the special sectional construction of the motor and fan casing 10 and in the manner of sustaining the lamp below the fan which in turn is below the motor which at any time may be conveniently inspected by opening the top or dome of the casing.
- 15 Having thus described our invention, what we claim and desire to secure by Letters Patent is:
1. In combination with the roof and ceiling of a vehicle, means for separating and 20 sustaining the same one from and upon the other, so as to provide a chamber between the two; a dome structure superposed upon the roof and continuing the said chamber above the latter; a fixture below the ceiling 25 and means for sustaining the same from the roof, said fixture being provided with a chamber; a motor in one of the chambers having its shaft extending into the other; a fan secured to said shaft and sustained thereby in the other chamber; and light-producing means sustained by said fixture.
  2. A combined fan and lamp comprising a supporting casing, an electric motor protectively sustained in the upper part of the 35 casing which has an openable top giving access to the motor, an electric lamp sustained at a lower part of the casing, and a fan arranged in an intermediate chamber of the casing formed between the motor and 40 the lamp and operatively coupled to the motor, said casing having openings forming air passages to and from its fan chamber.
  3. In combination with the ceiling and roof of a vehicle, means for sustaining the 45 ceiling from the roof and separating the same so as to provide a chamber therebetween; a superstructure and means for securing the same to the roof; dust-tight connections between the roof and the super- 50 structure; a fixture composed of a plurality of separable parts and means connecting the same to produce a chamber therein; means for securing the fixture to the ceiling and roof so as to cause the chamber of 55 the fixture and the first-named chamber to become coöperatively associated; a motor and means for sustaining the same from the roof within the superstructure and first-named chamber; and a fan disposed in the 60 chamber of the fixture and operatively connected to the motor so as to be driven thereby.
  4. In combination with the ceiling and a roof of a vehicle, means for sustaining the 65 ceiling from the roof and separating the same so as to provide a chamber therebetween; a superstructure and means for securing the same to the roof; dust-tight connections between the roof and the superstructure; a fixture composed of a plurality of 70 separable parts and means connecting the same to produce a chamber therein; means for securing the fixture to the ceiling and roof so as to cause the chamber of the fixture and the first-named chamber to become 75 coöperatively associated; a motor and means for sustaining the same from the roof within the superstructure and first-named chamber; a fan disposed in the chamber of the fixture and operatively connected to the motor so as to be driven thereby; the walls of the fan-chamber having a plurality of openings therein surrounding the fan structure; and means connected to the fixture for producing light.
  5. A combined fan and lamp comprising a sectional casing including an upper section having a horizontal flange, a second subjacent section having upwardly and downwardly extending flanges, means connecting 80 said two sections and adapted to clamp the horizontal flange of the upper section down upon a car roof while the horizontal part of the second section is forced upward to the car ceiling, a motor sustained by the upwardly extending flange of said second casing section, a third casing section held to the pendent flange of said second section, subjacent casing sections connected to said third casing section, a fan operatively coupled to 85 the motor for rotation thereby in a chamber formed within said third and next subjacent casing sections which have openings forming air passages to and from the fan chamber, and an electric lamp sustained by 90 the lowermost casing section below the fan.
  6. A combined fan and lamp comprising a sectional casing including an upper section having a horizontal flange, a second subjacent section having upwardly and downwardly extending flanges, means connecting 95 said two sections and adapted to clamp the horizontal flange of the upper section down upon a car roof while the horizontal part of the second section is forced upward to the car ceiling, a motor sustained by the upwardly extending flange of said second casing section, a motor guarding sleeve surrounding said upwardly projecting flange of the second casing section and passing upward within the vertical part of the upper casing section and surrounding portions of the motor above its sustaining flange, a third casing section held to the 100 pendent flange of said second section, subjacent sections connected to said third section, a fan operatively coupled to the motor for rotation thereby in a chamber formed within said third and next subjacent casing sections which have openings forming air 105 passages to and from the fan chamber, and an electric lamp sustained by the lowermost casing section below the fan.
  7. A combined fan and lamp comprising a sectional casing including an upper section having a horizontal flange, a second subjacent section having upwardly and downwardly extending flanges, means connecting 110 said two sections and adapted to clamp the horizontal flange of the upper section down upon a car roof while the horizontal part of the second section is forced upward to the car ceiling, a motor sustained by the upwardly extending flange of said second casing section, a motor guarding sleeve surrounding said upwardly projecting flange of the second casing section and passing upward within the vertical part of the upper casing section and surrounding portions of the motor above its sustaining flange, a third casing section held to the 115 pendent flange of said second section, subjacent sections connected to said third section, a fan operatively coupled to the motor for rotation thereby in a chamber formed within said third and next subjacent casing sections which have openings forming air 120 passages to and from the fan chamber, and an electric lamp sustained by the lowermost casing section below the fan.
  8. A combined fan and lamp comprising a sectional casing including an upper section having a horizontal flange, a second subjacent section having upwardly and downwardly extending flanges, means connecting 125 said two sections and adapted to clamp the horizontal flange of the upper section down upon a car roof while the horizontal part of the second section is forced upward to the car ceiling, a motor sustained by the upwardly extending flange of said second casing section, a motor guarding sleeve surrounding said upwardly projecting flange of the second casing section and passing upward within the vertical part of the upper casing section and surrounding portions of the motor above its sustaining flange, a third casing section held to the pendent flange of said second section, subjacent sections connected to said third section, a fan operatively coupled to the motor for rotation thereby in a chamber formed within said third and next subjacent casing sections which have openings forming air 130 passages to and from the fan chamber, and an electric lamp sustained by the lowermost casing section below the fan.

passages to and from the fan chamber, and an electric lamp sustained by the lowermost casing section below the fan.

7. A combined fan and lamp comprising 5 a sectional casing including an upper section having a horizontal flange, a second subjacent section having upwardly and downwardly extending flanges, means connecting said two sections and adapted to 10 clamp the horizontal flange of the upper section down upon a car roof while the horizontal part of the second section is forced upward to the car ceiling, a motor sustained by the upwardly extending flange of said 15 second casing section, a motor guarding sleeve surrounding said upwardly projecting flange of the second casing section and passing upward within the vertical part of the upper casing section and surrounding 20 portions of the motor above its sustaining flange, a packing interposed between the upper casing section and the car roof and also closely fitting said sleeve thereby preventing entrance of dust or moisture to the motor 25 from said roof, a third casing section held to the pendent flange of said second section, subjacent sections connected to said third section, a fan operatively coupled to the motor for rotation thereby in a chamber formed

within said third and next subjacent casing 30 sections which have openings forming air passages to and from the fan chamber, and an electric lamp sustained by the lowermost casing section below the fan.

8. A combined fan and lamp comprising 35 a support, an electric motor sustained at the upper part of said support, an electric lamp sustained at a lower part thereof, and a fan arranged in an intermediate chamber of the support formed between the motor and the 40 lamp and operatively coupled to the motor, said support having openings forming air passages to and from the fan chamber, and the fan having an upper outer series of substantially horizontal obliquely set blades and 45 a subjacent inner series of curved obliquely set blades, all of said blades coacting to direct air currents downwardly and outwardly to avoid injurious or disagreeable drafts upon persons below the lamp and fan. 50

In testimony whereof we have hereunto signed our names in the presence of two subscribing witnesses.

RALPH W. ARMSTRONG.
